UNITED STATES PATENT OFFICE.

SPENCER OTIS, OF CHICAGO, ILLINOIS, ASSIGNOR TO NATIONAL COAL
DUMP CAR COMPANY, OF RAPID CITY, SOUTH DAKOTA, AND CHI-
CAGO, ILLINOIS, A CORPORATION OF SOUTH DAKOTA.

DUMP-CAR

No. 815,032.

Specification of Letters Patent. Patented March 13, 1906.

Application filed December 26, 1903. Serial No. 186,643.

To all whom it may concern:

Be it known that I, SPENCER OTIS, a citizen of the United States, residing at Chicago, in the county of Cook and State of Illinois, have invented certain new and useful Improvements in Dump-Cars, of which the following is a specification.

My invention relates to that class of dump-cars which are provided with a supporting frame portion, side and end boards, and a drop-bottom portion formed of a plurality of swinging sections pivotally secured to the frame of the car at both sides of the longitudinal center.

The invention relates particularly to the means by which these swinging bottom sections are opened and closed, all of which will more fully hereinafter appear.

The principal object of the invention is to provide a drop-bottom dump-car formed of a plurality of swinging sections with simple, economical, and efficient mechanism for opening and closing the same.

Other and further objects of the invention will appear from an examination of the drawings and the following description and claims.

The invention consists, principally, in a drop-bottom dump-car in which there are combined a supporting-framework, a drop-bottom therefor formed of a plurality of swinging sections pivotally secured to the framework of the car, a plurality of pulleys with their axes transversely arranged and rotatably mounted on the supporting-frame of the car, chain mechanism securing such pulleys and swinging sections of the drop-bottom together, and means for operating or rotating such pulley mechanisms.

The invention consists, further and finally, in the features, combinations, and details of construction hereinafter described and claimed.

In the accompanying drawings, Figure 1 is a broken side elevation of a portion of one end of a car as it appears when constructed in accordance with these improvements, showing the drop-bottom sections in closed position as illustrated in Fig. 3; Fig. 2, a similar view showing the drop-bottom sections in open or discharging position as illustrated in Fig. 4; Fig. 3, a cross-sectional elevation of a portion of the car as it appears when constructed in accordance with these improvements, show-

ing the drop-bottom in closed position; and Fig. 4 a similar view showing the drop-bottom portions in open or discharging position.

In illustrating and describing these improvements I have only illustrated and will describe that which I consider to be new, taken in connection with so much as is old as will properly disclose the invention to others, and enable those skilled in the art to practice the same, leaving out of consideration other and well-known elements, which, if set forth herein, would only tend to confusion, prolixity, and ambiguity.

In constructing a dump-car in accordance with these improvements I provide a supporting-framework *a a* of any desired form and construction and prefer to use in connection therewith side and end boards *b* and *c*, respectively, which may be secured thereto in any convenient or usual manner.

To provide a drop-bottom portion for this dump-car, a plurality of swinging sections *d* are provided and pivotally secured at their inner edges to the supporting-framework of the car and at each side of the longitudinal center thereof. To open and close these drop-bottom swinging sections, a plurality of sheave-pulleys *e* are provided and rotatably mounted on the framework of the car transversely thereof underneath a housing *f* and adjacent to the side posts or stakes *g*. There is at least one of these sheave-pulleys for each swinging section, as shown particularly in Figs. 1 and 2, and each of these pulleys is provided with a chain *h*, which is secured thereto and to its respective swinging section at or near the free edge thereof. To rotate these sheave-pulleys, and thereby permit the opening and closing of the drop-bottom swinging sections, a sliding operating-bar *i* is provided and slidably mounted in the side frame of the car above and adjacent to its respective set of sheave-pulleys. A chain mechanism *j* runs from this sliding operating-bar to each sheave-pulley and to a groove separate and distinct from the groove in which the chains *h* are secured, so that there will be no interference or clogging during the operative movements of the parts.

It is necessary to move this sliding operating-bar in an efficient manner. For this purpose a main operating-shaft *k* is provided and rotatably mounted on the framework of the car—*i. e.*, in suitable bear-

ings in the end posts thereof, as shown particularly in Figs. 1 and 2. A chain *l* is connected with the end of this sliding operating-bar and wound around the main operating-shaft. This main operating-shaft has one or two square end portions and is further provided with a ratchet-wheel *m*, adapted to be engaged with a dog *n*, which will hold it, and thereby the sliding operating-bar, in any desired position—viz., to keep the doors closed or permit them to remain partially open—all of which will be understood and appreciated by those skilled in the art.

I claim—

- 15 1. A car of the class described having a bottom comprising swinging dumping-doors, and means for operating the doors comprising a longitudinally-movable member and a rotatable member and flexible connections between the longitudinally-movable member and the rotatable member and between the rotatable member and the doors.
- 20 2. In a dump-car of the class described, the combination of a supporting-framework, a drop-bottom portion formed of a plurality of swinging sections pivotally secured at their inner edges to the framework of the car at each side of the longitudinal center, a plurality of pulleys rotatably mounted on the
- 25 3. framework of the car transversely thereof—at least one for each swinging bottom section, chain mechanism securing the pulleys to the swinging bottom section, an operating-bar slidably mounted longitudinally of the car and adjacent to the pulley mechanism, chain mechanism securing said sliding bar to each and every pulley, and means for moving said sliding or operating bar, substantially as described.
- 30 4. In a dump-car of the class described, the combination of a supporting-framework, a drop-bottom therefor formed of a plurality of swinging sections pivotally secured thereto at their inner edges and at each side of the longitudinal center, a plurality of sheave-pulleys rotatably mounted on the frame of the car transversely thereof, chain mechanism securing such sheave-pulleys and drop-bot-

tom sections together, a sliding operating-bar arranged above and adjacent to said sheave-pulleys, chain mechanism securing said sliding bar to each and every sheave-pulley, a main operating-shaft rotatably mounted in the frame of the car transversely thereof, and chain mechanism securing such sliding bar to the main operating-shaft, substantially as described.

5. In a dump-car of the class described, the combination of a supporting-framework, a drop-bottom therefor formed of a plurality of swinging sections pivotally secured thereto at their inner edges and at each side of the longitudinal center, a plurality of sheave-pulleys rotatably mounted on the frame of the car transversely thereof, chain mechanism securing such sheave-pulleys and drop-bottom sections together, a sliding operating-bar arranged above and adjacent to said sheave-pulleys, chain mechanism securing said sliding bar to each and every sheave-pulley, a main operating-shaft rotatably mounted in the frame of the car transversely thereof, chain mechanism securing such sliding bar to the main operating-shaft, and ratchet-and-dog mechanism on said main operating-shaft to hold it in desired position, substantially as described.

6. In a dump-car of the class described, the combination of a supporting-frame portion, a drop-bottom therefor formed of a plurality of swinging sections pivotally secured to the framework of the car at each side of the longitudinal center, a longitudinally-movable slidably operating-bar, means connected with said slidable bar to close said swinging drop-bottom sections, and a main winding-shaft provided with chain mechanism connecting it with said slidable bar to operate the same and thereby close the swinging drop-bottom sections, substantially as described.

SPENCER OTIS.
